UNITED STATES PATENT OFFICE.

EDGAR H. FREEMAN, OF TRENTON, NEW JERSEY, ASSIGNOR TO E. H. FREEMAN ELECTRIC COMPANY, OF TRENTON, NEW JERSEY, A CORPORATION OF NEW JERSEY.

FACILE ASSEMBLY FOR LAMP-SOCKETS.

1,369,645.

Specification of Letters Patent. Patented Feb. 22, 1921.

Application filed October 21, 1916. Serial No. 126,992.

To all whom it may concern:

Be it known that I, EDGAR H. FREEMAN, a citizen of the United States, residing at Trenton, in the county of Mercer and State of New Jersey, have invented certain new and useful Improvements in Facile Assemblies for Lamp-Sockets, of which the following is a specification.

This invention relates to an improvement in electrical lamp sockets to facilitate the assembly and mounting thereof.

To this end the invention primarily has in view a novel construction for lamp sockets which provides a facile assembly of parts enabling the workman to assemble the socket with facility in the most difficult positions, as well as permitting the ready and easy removal of the socket parts as occasion may require. With the ordinary construction of lamp sockets, some locations and conditions render it exceedingly difficult for the workman to properly and securely place the socket in position and fasten together the socket parts. This is particularly true in applying the ordinary types of lamp sockets to the so-called husk fixtures wherein a cover or husk entirely surrounds and covers the lamp sockets. In applying the ordinary sockets to fixtures of that character, the wires are frequently twisted, and insecure and incomplete fastenings are effected between the socket parts, with the result of often leaving a dangerous condition existing at the fixture.

Furthermore, in many forms of construction it is exceedingly difficult and almost impossible for the workman to handle the socket parts in assembling the same within the narrow confines of the husk or cover. And this is equally true in cases of sockets mounted on fixtures in difficult and not easily accessible locations where it is almost impossible to bring the switch key into a readily accessible position to be operated.

The foregoing and other known objections to assembling and mounting ordinary types of lamp sockets are entirely obviated by the present invention, which provides, through the expedient of a simple and facile-assembly of parts, a means whereby the workman with ease, certainty and great facility, can quickly put together the parts

of the socket and mount the same in position on the fixture whether of the husk or ordinary types, and at the same time, without any difficulty, place the operating key for the switch in proper accessible position. Also the improved construction entirely obviates any objectionable twisting of wires.

A further distinctive object of the invention resides in the provision of novel means for supporting the lamp socket in such a manner that it may have a universal adjustment about its longitudinal axis, thereby permitting a key type of socket to be adjusted to any desired position.

A further object of the invention is to provide as a part of the socket mounting, a supporting member serving a number of useful functions; that is to say, a supporting member which permits of the universal circular adjustment of the socket upon its longitudinal axis, while at the same time acting as a nut element, combining with the socket body, to clamp in position a wiring base carrying the binding terminals or plates, and also as a nut element to lock the socket husk or cover in place when the invention is used with that type of fitting.

With these and other objects in view which will be appreciated by those familiar with this art, the invention consists in the novel construction, combination and arrangement of parts hereinafter more fully described, illustrated and claimed.

The invention is necessarily susceptible of structural change or modification without departing from the principle thereof, but for illustrative purposes a preferred and practical embodiment of the invention is shown in the accompanying drawings, in which—

Figure 1 is a sectional view of an electrical lamp socket of the key type, constructed in accordance with this invention and shown applied to a husk-fixture wherein a cover or husk entirely surrounds and covers the lamp socket.

Fig. 2 is a vertical, sectional view, illustrating the first step in the operation of applying the improved lamp socket construction to the lamp fixture bracket; the view showing in full lines the universal supporting member fitted to the pipe nipple, and by

dotted lines illustrating the simple means of applying said element.

Fig. 3 is a similar view showing by dotted lines respectively the manner of connecting 5 the wires with the wiring base and then drawing the latter to position within and against the supporting member.

Fig. 4 is a similar view illustrating the 10 final step in the operation of mounting the socket, that is the step of applying the socket body to the wiring base and connecting it, by fasteners, to the universal supporting element.

Fig. 5 is a perspective of the complete 15 socket construction showing the several members thereof in separated relation to clearly expose the directly coöperating elements thereof.

Fig. 6 is a longitudinal sectional view of 20 the socket body; the line of section being indicated by the line 6—6 of Fig. 5 of the drawings, and the view also showing, by dotted lines, the supporting member and the wiring base.

Similar reference numerals designate corresponding parts throughout the several figures of the drawings.

In carrying forward the invention the improved socket construction may be applied 30 to any lamp fixture bracket or piping without change or alteration therein, or in the fixture with which it is associated. Also, as indicated, a socket embodying the present invention is susceptible of easy application in difficult positions and locations, as for instance, in connection with a husk fixture, wherein it is almost impossible for the workman to apply the ordinary socket without meeting with the difficulties and 40 objections heretofore pointed out. Accordingly, for the purpose of illustrating the facility and ease with which the improved socket construction may be applied and adapted to a husk fixture, a fixture of this 45 type is illustrated in the drawings. Referring thereto, the numeral 1 designates an ordinary fixture bracket including the usual externally threaded pipe nipple 2 through which the wiring is strung, and in 50 the illustrated application of the invention, the fixture may also include the husk or socket covering 3 within which the socket proper is to be mounted.

The husk or socket covering 3 is shown 55 provided in its side with the usual key-receiving slot 4, and at its crown is provided with an opening to receive the pipe nipple 2, so that one member of the present invention may be utilized as an interior nut element for firmly clamping the husk or 60 socket covering against the shoulder of the pipe nipple.

The member of the improved socket construction which may perform the function 65 of an interior nut element to clamp the husk

or covering in position, represents one of the distinctive and important features of the present invention. It constitutes what may be termed a universal supporting member, and is designated in the drawings by the 70 reference numeral 5. This universal supporting member consists of a circular body of sheet metal or other suitable material, preferably hollowed out to form an interior recess or space 6, and provided at its 75 crown with a centrally disposed and interiorly threaded attaching neck 7 adapted to be screwed onto the threaded pipe nipple 2 and against the inner side of the crown 80 of the husk in cases where the latter is used on the fixture. In addition to its attaching neck 7, another feature of the universal supporting member 5 is that of the latter having an outturned holding flange 8, which is provided therein with a circular series 85 of equidistant threaded fastener holes 9, which constitute keeper elements for the socket-fasteners.

It will be observed from Fig. 5 of the drawings that the universal supporting 90 member 5 constitutes one member of a socket construction which preferably and usually also includes a socket body 10 carrying the contact elements, and a wiring base 11 carrying the binding terminals or 95 plates, and when the socket is applied to the fixture, the said member 5 constitutes the main supporting member to which is connected, and from which is supported, the said other members of the socket. This 100 feature of the invention is present in all embodiments thereof regardless of whether the wiring base and the socket body constitute a unitary structure or are separate parts as shown, and also regardless of the 105 fact whether the socket is of the key or of the keyless type. However, for the purpose of better illustrating the facility with which the present invention permits a key socket to be applied to a husk fixture, a 110 socket of the key type is shown in the drawings. In this illustrated embodiment of the invention it will be seen, particularly by reference to Figs. 5 and 6 of the drawings, that the socket body, designated in its entirety by the reference numeral 10, includes in its organization a body member 12 of porcelain or equivalent insulating material provided therein with the usual plug-receiving opening 13 and with a chambered base 120 portion 14. The said plug-receiving opening 13 has fitted therein in the usual manner the screw shell contact 15 and the center plug contact 16, the former having connected therewith a conductor screw 17 extending through the base 14 of the body member and electrically connecting with a contact plate or equivalent contact element 18 arranged in operative position at one end of the body member. This detail of the elec- 125 130

trical parts of the socket body is best seen in Fig. 5 of the drawings, and in this connection, it will also be noted that there may be utilized in this form of construction an insulating cover or diaphragm 18^a fitted over one end of the body member 12, so as to partly shield and cover the switch chamber.

The other side of the electrical circuit 10 within the socket body is completed through the switch mechanism and the center plug contact 16. This may be accomplished in any way without affecting the present invention, but in the illustration the said center plug contact 16 is shown fastened to the base of the plug-receiving opening 13 by a combined fastening and conducting screw 19, one end of which extends into the switch chamber of the base 14 and electrically connects with the pressure or snap-spring 20 of the switch mechanism. This mechanism also includes the usual key shaft 21 mounted in suitable bearings 22 formed at opposite sides of the base portion 14 and carrying 25 the usual switch key K and the rotatable switch block 23. The switch block 23 is engaged by the free end portion of the spring 20 and is located within one end portion of the switch chamber in the base portion 14, so it may be shifted in position for operative engagement with one of the binding plates carried by the wiring base 11, the other binding plate carried by said base being adapted to be in electrical contact with the 35 contact plate 18 when the various parts of the socket are fastened together and supported from the supporting member 5.

The wiring base 11 ordinarily may consist of a circular block of porcelain or 40 equivalent insulating material, and is chambered or recessed at one side to accommodate therein the oppositely arranged binding plates 24 and 25, the plate 24 being adapted to coöperate with the switch block 23, and the plate 25 being adapted for contact with the contact plate or equivalent contact 18 of the socket body. Each of the 45 said binding plates 24 and 25 carries the usual binding screw 26 to which is connected one of the wire terminals which is lead through the fixture piping. In addition to the recessed formation at one side thereof, the body of the wiring base 11 is formed on its upper side with a central annular projection 27 constituting what might be termed a projecting centering guide which has a registering engagement and fit within the recessed inner side 6 of the supporting member 5. Also the body of 55 the wiring base is preferably provided at one or more points with positioning guide projections 28 adapted to engage with complementary guide recesses or equivalent elements 29, the said elements 28 and 29 being 60 adapted to interfit in order to properly locate the fastener elements carried by the socket body.

As indicated, the sole fastening means for the socket construction are carried by the socket body. These fastening means perform no electrical function and may simply consist of a pair of oppositely arranged fastener screws 30 loosely mounted in keeper openings 31, formed longitudinally in the base portion 14 of the socket member 12, the 70 heads of the said fasteners being exposed to and accessible through the plug-receiving opening of the socket so that the workman can easily and conveniently bring the socket parts together and fasten them by a simple 75 act of manipulating a screw driver through the plug-receiving opening of the socket. The said fastener screws 30 are of sufficient length to extend a substantial distance beyond one end of the socket body, so that 80 they can pass entirely through the retainer openings 32, extending through the body of the wiring base 11, the end portions of the fasteners 30 being threaded, so as to engage any of the threaded fastener holes in the 85 holding flange 8 of the supporting member 5.

In applying the improved socket construction to the fixture bracket it is simply necessary to first place the universal supporting member 5 in the position shown in Fig. 2 of the drawings. This may be conveniently and readily accomplished by the use of a light spanner wrench 33, shown in dotted lines in Fig. 2 of the drawings. This 100 spanner wrench may be formed with a tubular shank 34 so as to easily work over the drawn out wires W. One end of the tubular shank 34 carries the wrench studs 35 to engage diametrically opposite holes 9 of the 105 supporting member 5, the other end of the tubular shank carrying a suitable handle 36. It is obvious in the use of a tool of the character referred to that the workman after pulling the wires out of the pipe nipple to 110 a position where he can conveniently manipulate the separate wire terminals, that it is only necessary to slip the member 5 and the tool 34 over the wire and by means of the tool the supporting member 5 can be 115 firmly screwed onto the pipe nipple 2. After thus positioning the supporting member 5, the wiring base 11 may be placed over the wire ends, as shown by the dotted lines in Fig. 3 of the drawings thereby permitting the wiring to be located within the central wire opening 37 of the wiring base and the separate wire ends secured to the binding plates 24 and 25 by the binding screws 26. Then, in order to position the 120 wiring base with the wire ends attached thereto, it is only necessary for the workman to draw the wiring back through the fixture with the result of carrying the wiring base into clamping contact and registra- 125 130

tion with the supporting member 5, this part of the assembling being facilitated by the automatic engagement of the annular guiding projection 27 with the central recessed part of the supporting member 5.

With the supporting member and the wiring base properly positioned, as illustrated in Fig. 3 of the drawings, the socket body is then placed against the wiring base with the fastener screws 30 extending through the retainer openings 32, thus permitting the said screws to be screwed into any part of diametrically opposite fastener holes 9 of the supporting member. In this connection, it will be observed that when applying the improved socket construction to a husk fixture it is necessary to first slightly tilt or incline the socket body, as indicated by the dotted lines of Fig. 4 of the drawings, to insert the key K through the key slot 4, after which the socket body is clamped against the wiring base in the manner explained. In the operation of assembling parts the coöperating guide elements 28 and 29 serve to assist the workman in bringing the socket body and the wiring base together with the fastener screws 30 in position to enter the retainer openings 32 in the body of the wiring base.

While the invention has been described in connection with a socket of the porcelain uncovered type, it will be understood that the same is not limited to a socket of this kind because the improved features of construction are equally well adapted to sockets which are inclosed within sheet metal casings consisting of the conventional sheet metal cap and shell members. Also it will be understood that various changes in the form proportion and minor details of construction may be resorted to, within the scope of the appended claims, without departing from the scope of the invention or sacrificing any of the advantages thereof.

I claim:

1. A lamp switch socket construction including in combination, a hollow supporting member having fixture attaching means, a socket body carrying the two lamp terminals and the manually actuated part of the switch mechanism, an intermediate wiring base capped by said hollow supporting member and arranged to form a cover for one end of the socket body, the said wiring base carrying the binding terminals and an element of the switch mechanism, and fastening means carried by the socket body and having a holding engagement with the said hollow supporting member.

2. A lamp socket construction including a supporting member having fixture attaching means, and a multiplicity of keeper elements, a socket body carrying fasteners engaging with any of said keeper elements, and a separate wiring base clamped between the socket body and the supporting member.

3. A lamp socket construction including a supporting member having a circular series of fastener holes, a socket body carrying fasteners engaging any of said holes, and a separate wiring base clamped by the socket body to the supporting member.

4. A lamp socket construction including a supporting member having a flange provided with a circular series of threaded holes, a socket body carrying threaded fastener screws engaging any of said holes to provide for the universal adjustment of the said socket body, and a circular base clamped between the socket body and the supporting member.

In testimony whereof I hereunto affix my signature in the presence of two witnesses.

EDGAR H. FREEMAN.
